FIG.1

FIG.2

Inventor:
John Francis Booth
by Alfred Allen

UNITED STATES PATENT OFFICE.

JOHN FRANCIS BOOTH, OF RAETIHI, WELLINGTON, NEW ZEALAND.

SHIP'S BILLARD-TABLE.

1,248,797.

Specification of Letters Patent.

Patented Dec. 4, 1917.

Application filed April 4, 1917. Serial No. 159,660.

To all whom it may concern:

Be it known that I, JOHN FRANCIS BOOTH, subject of the King of Great Britain, residing at Raetihi, Wellington, in the Dominion of New Zealand, have invented new and useful Improvements in Ships' Billiard-Tables; and I do hereby declare the following to be a full, clear, and exact description of the same.

10 This invention has been devised in order to provide improved means for supporting a billiard table to adapt it for use on a ship and which means are designed to support the table in such a manner that it will be maintained level and steady when the ship pitches and rolls. The means employed also provide for the table being supported in such a manner as to withstand the ordinary weight placed on its edge by a person 20 playing.

In carrying out the invention the table is supported at its exact center upon a single pillar on top of which the table rests on a ball and socket joint so that the table may be able to swing up and down relatively to the pillar.

Beneath each corner of the table is arranged a vertical cylinder of approved diameter and these four cylinders are arranged in communication with each other through conduits of a cross sectional area equal to that of each cylinder. Water is placed in the four cylinders and their communicating conduits so that the level of the

30 top surface in the four cylinders will automatically remain constant with regard to the normal stationary level, no matter how the ship's deck on which the cylinders rest alters its level with the movements of the ship.

40 Extending downward from the table at each corner is a vertical bar to the bottom end of which a float is attached and which float approximately fits the corresponding water cylinder beneath. The buoyancy of these

45 floats in the water is adjusted to support the table at its four corners with a sufficient upward resistance to prevent its displacement downward when ordinary playing weight is imposed on any particular part of the table's edge. The floats also in their support of the table serve to keep it normally level, the floats responding with the variations in the relative level of the water in the cylinders caused by the movements 50 of the ship.

In order to restrain the table from any

side swing, while permitting of the relative movement of the table supports, a rod or pair of rods is or are fixed to depend from each end thereof and to pass through an eye, or eyes upon a bracket or standard fastened to the deck beneath. These permit of the deck swaying, the eyes running freely over the rods and leaving the table stationary.

60 The invention is illustrated in the accompanying drawings, in which:—

Figure 1 is a side elevation of a table and its support, portion of the water cylinders being shown in section.

70 Fig. 2 is a plan of the table supports, the table being indicated in dotted lines.

A is the table top which is made in any of the usual ways but for the purposes of this invention will preferably be stiffened by suitable metal braces extending in approved manner, diagonally for instance across its underside. B is the central supporting pillar that is firmly fixed to the deck C and is provided with an approximately semi-spherical top end D of metal or other wear resisting material. E is the socket piece fastened to the underside of the table and positioned at the exact center thereof and which socket piece is adapted to fit on to the top D of the pillar so as to form a pivotal support upon which the table may rock in any direction.

75 F are the four vertical water cylinders arranged beneath the respective four corners of the table. These have their bottom ends all connected together by cross cylinders or conduits G, of equal cross sectional area to the vertical cylinders, in order to provide for an instantaneous and equal displacement of the water in the vertical cylinders, with the variations in the relative levels thereof caused by the movements of the deck to which the cylinders are fixed. The vertical cylinders are arranged to project 80 upward to any convenient height such as not to interfere with the free rocking of the table A, on its central support, within reasonable limits. They are arranged to extend down through the deck, while the horizontal cylinders are arranged along below such deck.

90 H are the floats, one of which is placed within each vertical cylinder F, and is attached to a rod J extending downward from the bottom of the corresponding table corner. The attachment of these rods to the

table are preferably of a nature such as to allow of the relative angle of the rods to the table varying with the alterations in the table's level relative to the deck. This may be effected by providing each rod with an elbow joint J' which permits of this movement and at the same time sustains the vertical upward thrust of the floats' buoyancy.

The water level in the cylinders is adjusted to provide for the submerging of the floats to the extent necessary to provide the buoyancy requisite to sustain the weight of the table, and also the weight placed on any particular part of the table by an individual leaning thereon to play. The floats also are made of such an area and the cylinders of such a diameter as to provide for such buoyancy being obtained.

K, K are the brackets fixed to the deck beneath each end of the table and having horizontal members at a suitable height above such deck formed with the eyes k therein. M are rods fixed to the table and depending vertically therefrom and passing loosely through the respective eyes k . These rods by their engagement in the eyes restrain any side swinging of the table while permitting its rocking on the central pivotal support.

30 I claim:—

1. In ships' billiard tables, a fixed pillar upon which the center of the table is piv-

otally supported, in combination with vertical cylinders arranged one beneath each corner of the table and having their lower ends in communication with one another, a float situated in each vertical cylinder and a rod extending from such float to the corresponding corner of the table, substantially as and for the purposes specified.

2. A ship's billiard table formed by a playing table top pivotally supported at its center upon a fixed pillar and supported at each of its four corners upon floats contained within fixed cylinders or tanks of water, substantially as specified.

3. In ships' billiard tables, a fixed pillar upon which the center of the table top is pivotally supported, a vertical cylinder arranged beneath each corner of the table top, a float fitted in each cylinder and attached to the corner of the table top above it, fixed brackets situated beneath the table top and having eyes therein, and rods fixed to the table top and extending vertically and loosely through the respective eyes, substantially as and for the purposes specified.

In testimony whereof, I have signed this specification in the presence of two subscribing witnesses.

JOHN FRANCIS BOOTH.
